UNITED STATES PATENT OFFICE.

GEORGE O. DRAPER, OF HOPEDALE, MASSACHUSETTS, ASSIGNOR TO
GEO. DRAPER & SONS, OF SAME PLACE.

SELF-THREADING LOOM-SHUTTLE.

SPECIFICATION forming part of Letters Patent No. 591,370, dated October 5, 1897.

Application filed January 11, 1896. Serial No. 575,093. (Model.)

To all whom it may concern:

Be it known that I, GEORGE O. DRAPER, of Hopedale, county of Worcester, State of Massachusetts, have invented an Improvement 5 in Self-Threading Loom-Shuttles, of which the following description, in connection with the accompanying drawings, is a specification, like letters and figures on the drawings representing like parts.

10 This invention has for its object the production of a simple and cheap self-threading shuttle for looms, whereby as the shuttle is thrown across the warps and back again the filling-thread is automatically guided into 15 the open eye in the side of the shuttle, whence it is delivered in the subsequent travel of the shuttle.

Figure 1 is a perspective view of a self-threading loom-shuttle embodying my invention. Fig. 2 is an enlarged right-hand side elevation of the delivery end of the shuttle shown in Fig. 1. Fig. 3 is a top or plan view thereof with the threading device removed, but partially indicated in dotted lines. Fig. 25 4 is a rear elevation, and Fig. 5 a side elevation, of the threading device removed.

The shuttle-body A is shown as longitudinally slotted from top to bottom at a to receive a suitable filling-carrier or bobbin B, 30 (shown only in Fig. 1,) and at the delivery end of the shuttle a concavity a' is made, communicating with a transverse slot b in the side of the shuttle, forming the thread-eye. Above the said eye the material of the 35 shuttle-body is rearwardly and downwardly inclined at b', to the more readily guide the filling-thread to the eye in the act of threading.

The front wall a² of the slot or opening a is partially cut away to leave a longitudinal 40 wall a³, forming one side of the thread-receiving opening near the point of the bobbin or filling-carrier B. The opposite side of said opening is almost closed by a pin c, depending from the head d' of a metallic stud d 45 nearly to the bottom of the thread-receiving opening in front of and slightly to one side of the point of the filling-carrier, the stud, as clearly shown in Fig. 3, being eccentrically located in the concavity a'.

50 A countersunk hole e is bored in the shuttle-body at the bottom of the concavity a' and at

one side of the longitudinal center of the shuttle to receive the enlarged foot or base d² of the said stud, which latter is provided with a threaded hole to engage a retaining-screw s, 55 (see dotted lines, Fig. 2,) inserted through the hole e in the shuttle-body.

The stud d acts as a post or pin around which the thread is led to the side eye b, being guided thereto by the mushroom or umbrella shaped top d' of the stud, around the periphery of which the thread passes and between it and the concavity a'.

As shown in Figs. 1 and 4 and by dotted lines, Fig. 3, the head d' is slabbed off at d^X 65 to fit against the transverse wall a⁴, extending part way across the shuttle, and a steady-ing-pin d³, secured to the head, is adapted to enter a suitable hole 3 in the shuttle at the rear side of the side eye b, preventing turning 70 of the stud d and also forming a metallic side for the eye b.

The pin c depends from the straight side d^X of the head d' and is curved inward toward the longitudinal center of the shuttle, as best 75 shown in Fig. 4, so that it serves as a guide to direct the thread beneath it and into the space between it and the side a³ as the thread unwinds from the point of the filling-carrier.

After the thread has passed beneath it the 80 pin c acts to retain the thread in the receiving-opening, whence it passes around the stud d and beneath its head d'. This position of the thread is brought about by the first throw of the shuttle, and on the return throw the 85 mushroom-like head d' guides the thread between it and the inclined wall b' into the side eye b, from which it is subsequently delivered.

The construction herein described is very simple and cheap and threads the shuttle automatically in a rapid and effective manner. 90

Having described my invention, what I claim as new, and desire to secure by Letters Patent, is—

1. A self-threading shuttle having an open 95 side eye, a thread-receiving opening in the front end wall of the bobbin-receiving slot, a stud in advance of said opening having a laterally-extended head slabbed off at its rear side to fit against said end wall, a downturned 100 pin thereon curved inward toward the longitudinal center of the shuttle, forming one

side of and nearly closing the thread-receiving opening, through which the thread passes to and around the stud, and a steadyng-pin secured to the head and entering the shuttle 5 at the rear wall of the side eye, substantially as described.

2. A self-threading shuttle having an open side eye, a concavity in the top of its delivery end, and a transverse wall having a thread-receiving opening, an eccentrically-located internally-threaded stud adjacent thereto, having a laterally-extended head, convexed on its under side and slabbed off at its rear side, to fit against the transverse wall, and 15 a retaining-screw to enter the internally-

threaded stud from the bottom of the shuttle, a free passage for the thread being provided on three sides of the stud between the under side of the head and the concavity, to guide the thread to the side eye, the shuttle being 20 rearwardly and downwardly inclined above the latter, substantially as described.

In testimony whereof I have signed my name to this specification in the presence of two subscribing witnesses.

GEORGE O. DRAPER.
